H. BARNES

GOLF CLUB

Filed Oct. 29, 1920

INVENTOR
Helfron Barnes
BY
Thomas L. Wilder
ATTORNEY

UNITED STATES PATENT OFFICE.

HEFFRON BARNES, OF NEW YORK MILLS, NEW YORK.

GOLF CLUB.

Application filed October 29, 1920. Serial No. 420,514.

To all whom it may concern:

Be it known that I, HEFFRON BARNES, a citizen of the United States, residing at New York Mills, in the county of Oneida 5 and State of New York, have invented certain new and useful Improvements in Golf Clubs, of which the following is a specification, reference being had therein to the accompanying drawing.

10 My invention relates to a golf club and I declare the following to be a full, clear, concise and exact description thereof sufficient to enable anyone skilled in the art to which it appertains to make and use the 15 same, reference being had to the accompanying drawings in which like reference characters refer to like parts throughout the specification.

The object of the invention is to provide a 20 golf club that will have an adjustable head relative to the shaft, whereby the club can be made to fit the stance of any golf player regardless of said player's height or characteristics. Such an adjustment of the head 25 to the shaft is more particularly desirable with reference to the golf club known as the putter used for driving the golf ball for short distances over a green into a hole, where a great degree of accuracy is required. 30 To this end the club is equipped with a head that is pivotally mounted to the shaft. Mechanism is provided also to lock said parts at any desired angle that conforms to the proper stance of the player using the 35 golf putter. When once this angle is ascertained, the parts will be rigidly set to prevent any further movement thereof, whereby to maintain that certain angle which most nearly conforms to the stance of the 40 user of said club.

The object will be understood by referring to the drawings in which:

Fig. 1 is a perspective view of the golf club embodying the improvement, showing 45 the shaft broken away;

Fig. 2 is a detail perspective view of an annular thumb nut employed, showing the same mounted upon a bolt also employed;

Fig. 3 is a side elevation, looking at the 50 rear side thereof, of a modified form of golf club;

Fig. 4 is a perspective view of a still further modified form of golf club, the shaft being removed therefrom;

55 Fig. 5 is a perspective detail view of the shaft that fits the head shown in Fig. 4;

Fig. 6 is an end elevation of the golf club shown in Fig. 1;

Fig. 7 is an elevational view of the golf club, showing the side opposite to that 60 illustrated in Fig. 1.

Fig. 8 is a perspective view of another modified form of the golf club, showing the junction of the head with the shaft and looking at said parts which are slightly 65 tipped at an angle.

Referring more particularly to the drawings, the head —1— of the golf club has a recess or socket at 2 where the shaft 3 is pivotally joined thereto. The lower end 70 of said shaft 3 is reduced at 4 to form a tongue that sets down into the socket 2 formed in part 5 of the head —1— and is pivotally united to said part 5 by a headed bolt 7. The bolt 7 projects through the 75 walls of part 5 and through the lower end or tongue 4 of shaft 3.

Said head —1— is held at any desired angle relative to the shaft 3, whereby to adapt the golf club, particularly the putter, 80 to the stance of the player using said club by a bolt 10 that also passes through the walls adjacent the socket 2 and through the tongue 4. For this purpose the walls are provided with slots 11, 11 that are formed 85 on the arc of a circle to receive and allow the projecting ends of the bolt 10 to move therein to adjusted position. On one side the slot 11 has a counter sunk recess 11^a formed adjacent thereto for the disposition 90 of head 10^a of bolt 10, whereby said head 10^a will fit flush with the contiguous surface of head —1—. However, when head —1— is moved relative to the shaft 3 and the correct angle ascertained to conform to the stance of the player using the club, said head —1— and shaft 3 will remain fixed thereafter and not be moved except at the will of the player.

In order to hold thus the head —1— and shaft 3 relative to each other, an annular thumb nut 12 having a serrated periphery 13 and slot 13^a for the disposition therein of the end of a screw driver, is screw mounted to the bolt 10. Said thumb nut 12 has a central boss 14 that is adapted to make contact and bind against the adjacent surface of the head —1— when said nut is screwed up tight along the bolt 10. The turning of the thumb nut 12 upon the bolt 10 will draw the bolt 10 towards said 105 nut 12 and thereby cause the upper parts of the walls adjacent the socket 2 in part

5 of head —1— to bind rigidly against the adjacent sides of tongue 4 at the angle to which it is set with reference to shaft 3. A screw driver may be applied to the slots 6 13^a to further tighten the thumb nut 12.

Figs. 4 and 5 show a modified manner of holding the head —1— relative to the shaft 3. Here the head —1— is provided with an end part 15 that has a plurality of 10 radial teeth 16, adapted to mesh with the complementary teeth 17 formed on the lower annular part 18 of shaft 19. A headed bolt and nut are employed to hold said head and shaft together. The teeth 16 and 15 17 are made very small to permit a very accurate adjustment of the head —1— relative to the shaft 19.

The modification of the golf club illustrated in Fig. 3, shows a club adapted for 20 use by either a right or left hand player. Here the head 20 has a central recess or socket for the reception of the lower reduced end 21 of the shaft 22, which is pivotally united to said head 20 by a headed bolt 23 that passes through the walls 25 of the socket in head 20 and through the reduced end 21 of said shaft 22, much in the same manner as already described with reference to the former construction illustrated in Figs. 1, 6 and 7.

The head 20 is held at any given angle relative to shaft 22, whereby to make the club conform to the stance of a right or left hand player by a headed bolt 24 and annular thumb nut 25 having a serrated periphery and slot 26, for the disposition of the end of a screw driver. The bolt 24 passes through the lower reduced end 21 of shaft 22. Its free ends rest in the elongated recesses 27, 27 formed in the walls adjacent the socket in head 20. Said recesses are slightly curved to permit of the movement of the ends of the bolt to adjusted position. One of the free ends of said bolt 40 45 24 subjects through its corresponding recess 27 and extends sufficiently far for the mounting of the annular thumb nut 25, as in the former construction.

Fig. 8 shows a still further modification. 50 Here the head 30 has its end part equipped with a plurality of sockets formed between walls 31 of said part. The shaft 32 has also a plurality of tongues 33 adapted to fit down into said sockets formed between the

walls 31. A headed bolt 35 and annular 55 thumb nut 36 similar to those heretofore described are used to hold the shaft 32 and head 30 at any desired angle that will conform to the stance of the player. A washer 38 is mounted on the bolt 35 so as 60 to come between the surface of the annular thumb nut 36 and that of the head 30 to provide clearance between said surfaces.

When the thumb nut 36 is tightened sufficiently it will cause the several walls 65 31 and tongues 33 to bind together, whereby to hold in a rigid manner the head 30 relative to the shaft 32. The bolt 35 will be employed alone in this construction without the aid of another bolt to act as a separate fulcrum. The head of bolt 35 is countersunk in outside wall 31 of head 30.

Having thus described my invention what I claim as new and desire to secure by Letters Patent is:

1. In a golf club, a head, a shaft, said shaft being pivotally mounted to said head, said head having formed thereon a plurality of walls with sockets therebetween, said shaft having a plurality of tongues formed thereon, said tongues adapted fit within said sockets, recesses made in said tongues and walls, a bolt adapted to fit within said recesses, and a thumb nut screw mounted to said bolt, whereby to bind the tongues and walls to hold the head in given adjusted position with reference to said shaft, and a washer for holding the thumb nut away from the surface of the head.

2. In a golf club, a head, a shaft, said shaft being pivotally mounted to said head, said head having formed thereon a plurality of walls with sockets therebetween, said shaft having a plurality of tongues formed thereon, said tongues adapted fit within said sockets, recesses made in said tongues and walls, a bolt adapted to fit within said recesses, and a thumb nut screw mounted to said bolt, whereby to bind the tongues and walls to hold the head in given adjusted position with reference to said shaft, and a washer for holding the thumb nut away from the surface of the head, and said head of the bolt being countersunk in a wall of the head.

In testimony whereof I have affixed my signature.

HEFFRON BARNES.
